(57) **CLAIM**

The ornamental design for a center console with privacy divider for passenger seat, as shown and described.

DESCRIPTION

FIG. 1 is a front perspective view of a center console with privacy divider for passenger seat showing our new design. FIG. 2 is a front view of the center console with privacy divider for passenger seat of FIG. 1.

FIG. 3 is a rear view of the center console with privacy divider for passenger seat of FIG. 1.

FIG. 4 is a left side view of the center console with privacy divider for passenger seat of FIG. 1.

FIG. 5 is a right side view of the center console with privacy divider for passenger seat of FIG. 1.

FIG. 6 is a top view of the center console with privacy divider for passenger seat of FIG. 1.

FIG. 7 is a bottom view of the center console with privacy divider for passenger seat of FIG. 1; and,

FIG. 8 is a front perspective view of the center console with privacy divider for passenger seat of FIG. 1 incorporated into a row of passenger seats.

The dash-dot broken lines immediately adjacent to shaded areas represent unclaimed boundaries of the claimed design. The remainder of the center console with privacy divider for passenger seat shown in broken lines shows unclaimed subject matter only and forms no part of the claimed design.

1 Claim, 8 Drawing Sheets
